UNITED STATES PATENT OFFICE.

MAX KUSHNER, OF BROOKLYN, NEW YORK.

DESIGN FOR A PANEL FOR LAMP SHADES OR SIMILAR ARTICLES.

Application filed October 6, 1928. Serial No. 28,385. Term of patent $3\frac{1}{2}$ years.

To all whom it may concern:

Be it known that I, MAX KUSHNER, a subject of Rumania, a resident of Brooklyn, in the county of Kings, State of New York, whose post-office address is 1893 West 12th Street, borough of Brooklyn, city of New York, State of New York, have invented a new, original, and ornamental Design for a Panel for Lamp Shades or Similar Articles,

of which the following is a specification, reference being had to the accompanying drawing, forming part thereof.

Figure 1 is a plan view of my new design. Figure 2 is an edge view of the same.

I claim:

The ornamental design for a panel for lamp shades or similar articles as shown.

MAX KUSHNER.
